COMBINED MAGAZINE RACK AND TOILET TISSUE HOLDER

Carroll S. Delaney, Denver, Colo.

Application September 29, 1954, Serial No. 32,475

Term of patent 7 years

(Cl. D4—3)

FIG. 1.

FIG. 2.

To all whom it may concern:

Be it known that I, Carroll S. Delaney, have invented a new, original, and ornamental Design for a Combined Magazine Rack and Toilet Tissue Holder, of which the following is a specification, reference being had to the accompanying drawing, forming a part hereof.

Figure 1 is a perspective view looking downward and to the right on a combined magazine rack and toilet tissue holder showing my new design; and,

The side not shown is identical with the side shown except reversed.

I claim:

The ornamental design for a combined magazine rack and toilet tissue holder, as shown and described.
